CLAIM

The ornamental design for a lighting apparatus as shown and described.

DESCRIPTION

FIG. 1 is a perspective view of a lighting apparatus;

FIG. 2 is a front view thereof;

FIG. 3 is a rear view thereof;

FIG. 4 is a bottom view thereof;

FIG. 5 is a top view thereof;

FIG. 6 is a left-side view thereof; and,

FIG. 7 is a right-side view thereof.

The set of longer broken lines shown in FIG. 4 in the drawings represent portions of the lighting apparatus that form no part of the claimed design. The set of shorter broken lines in FIGS. 1 and 4-7 represent symbolic break lines. The symbolic break lines, as well as portions between the break lines, form no part of the claimed design.

1 Claim, 6 Drawing Sheets
